US00D515683S

(12) **United States Design Patent** (10) Patent No.: **US D515,683 S**
LaBlaine (45) Date of Patent: **** Feb. 21, 2006**

(54) **AIR FRESHENER DEVICE**

(75) Inventor: **Bruno LaBlaine**, c/o ABN Concept - Design Packaging, 7 rue Paul Langevin, Mainvilliers (FR), 28300

(73) Assignee: **Bruno LaBlaine**, Slough (GB)

(**) Term: **14 Years**

(21) Appl. No.: **29/209,903**

(22) Filed: **Jul. 23, 2004**

(30) **Foreign Application Priority Data**

Jan. 30, 2004 (EP) 000128582

(51) **LOC (8) CI. 23-04**

(52) **U.S. CI. D23/366**

(58) **Field of Classification Search** ..... D23/356-369; 392/390, 392, 393, 394, 398; 239/34, 53, 239/56, 57, 58, 135, 136; 261/DIG. 17, DIG. 65, 261/DIG. 88, DIG. 89; D6/470, 471; D9/414, D9/430, 431; D30/101
